J. NEEDHAM.
GAS MIXER.
APPLICATION FILED JAN. 8, 1921.

1,411,063.

Patented Mar. 28, 1922.

Inventor
Joseph Needham
By his Attorney
Edgar Dale Jr.

UNITED STATES PATENT OFFICE.

JOSEPH NEEDHAM, OF PASSAIC, NEW JERSEY.

GAS MIXER.

1,411,063.

Specification of Letters Patent. Patented Mar. 28, 1922.

Application filed January 8, 1921. Serial No. 435,828.

To all whom it may concern:

Be it known that I, JOSEPH NEEDHAM, a subject of the King of Great Britain, and residing at Passaic, in the county of Passaic 5 and State of New Jersey, have invented certain new and useful Improvements in Gas Mixers, of which the following is a specification, such as will enable those skilled in the art to which it appertains to make and 10 use the same.

This invention relates to gas mixers and particularly to devices of this class adapted for use in connection with fuel gas furnaces and like appliances, and the object of the 15 invention is to provide a device of the class specified composed of a suitable body portion having a fuel chamber, a mixing chamber formed therein with an air chamber therebetween and an adjustable tubular 20 member which forms a part of the mixing chamber of the device, and which is provided with an outwardly flaring throat in connection with which a fuel discharge device or nozzle, in communication with the fuel 25 chamber, operates, and with this and other objects in view the invention consists in a device of the class and for the purpose specified which is simple in construction and operation, and which is constructed as herein- 30 after described and claimed.

The invention described and claimed herein is an improvement on that described and claimed in a prior patent granted to me October 19, 1920, No. 1,355,998, and is fully 35 disclosed in the following specification, of which the accompanying drawing forms a part, in which the separate parts of my improvement are designated by suitable reference characters in each of the views, and in 40 which;—

Fig. 1 is a plan view of my improved gas mixing device;

Fig. 2 a section on the line 2—2 of Fig. 1; and,

Fig. 3 a view similar to Fig. 2 but showing a slight modification.

In the construction shown in Figs. 1 and 2, my improved gas mixing device comprises a body portion 5 composed of separate parts 50 6 and 7, the part 6 being provided with a fuel chamber 8 having an intake port 9 and a discharge nozzle 10. The part 7 is tubular in form and provided with a mixing chamber 11, one end of the part 7 is provided with an enlarged head 12 and the adjacent end of the part 6 with a similar head

13 having arms 14 extending in the direction of the head 12 and by means of which the separate heads 12 and 13 are connected by bolts or screws 15 passed through the head 60 12 and into the arms 14. This construction forms an air space 16 between the separate parts 6 and 7, or between the discharge nozzle 10 of the fuel chamber and the mixing chamber 11. 65

A tubular member 17 is adjustably mounted in the part 7 of the device and partially forms the mixing chamber 11 of said part 7, clearly shown in Fig. 2 of the drawing and the throat 18 of said mixing chamber flares 70 outwardly as shown at 19 into the air space 16, and said end of the tubular member 17 is provided with an enlarged head 20, in the periphery of which are spaced apertures 21 adapted to receive a spanner wrench or 75 the like to permit of the adjustment of said tubular member in the part 7.

It will be noted that in Fig. 3 of the drawing, the body portion 5 of the device is made in one piece, or the ends 6 and 7 are made 80 integral, and with this exception the remainder of the device is the same as that shown in Figs. 1 and 2.

It will be noted that in both forms of the construction shown, the discharge nozzles 10 are detachably mounted in the body portion as are also the tubular members 17, and these members are also adjustably mounted in the end or part 7 of the device whereby the position of the throat 18 of the mixing 90 chamber 11 relatively to the nozzle 10 may be regulated so as to control the entrainment of air through said throat into the mixing chamber in the passage of high pressure fuel through said nozzle. 95

It will be apparent that while I have shown certain details of construction for carrying my invention into effect, I am not necessarily limited to these details, and various changes in and modifications of the 100 construction herein shown and described may be made, within the scope of the appended claims, without departing from the spirit of my invention or sacrificing its advantages.

Having fully described my invention, what I claim as new and desire to secure by Letters Patent, is:—

1. A device of the class described comprising a suitable body portion having a fuel chamber, a mixing chamber and an air space therebetween, a tubular member rota- 110

5 tably adjustable in the body portion and forming part of said mixing chamber, and the throat of which flares outwardly into said air space, and means for discharging fuel from said fuel chamber into said mixing chamber through said throat.

- 10 2. A device of the class described comprising a suitable body portion at one end of which is a fuel chamber and a mixing chamber at the other end portion thereof and between which and said fuel chamber is an air space, a fuel discharge device detachably connected with said body portion and in communication with said fuel chamber, a 15 tubular member adjustably mounted in said body portion and extending into the mixing chamber and forming part thereof and provided with a reduced and outwardly flaring throat, the position of which relatively to 20 said fuel discharge device will control the entrainment of air into said mixing chamber through said throat.

- 25 3. A device of the class described comprising a suitable body portion having a fuel chamber at one end thereof and a mixing chamber at the other end thereof, said fuel chamber and mixing chamber being joined by an air space, a tubular member ad-

justably mounted in the body portion and being provided with an outwardly flaring throat which opens into the air space and said member being in communication with and forming part of said mixing chamber, and a fuel discharge nozzle detachably mounted in connection with the first named 30 end of the body portion and extending into said air space, and a tubular member adjustably mounted in the last named end of the body portion and extending into said mixing chamber and forming part thereof, said 35 tubular member being provided with an outwardly flaring throat which communicates with said air space whereby the adjustment of said tubular member toward and from said fuel discharge device will control 40 the entrainment of air into the mixing chamber through said throat.

In testimony that I claim the foregoing as my invention I have signed my name in presence of the subscribing witnesses this 5th 50 day of January, 1921.

JOSEPH NEEDHAM.
